UNITED STATES PATENT OFFICE.

JOSEPH BORYSZEWSKI, JR., OF FORKS, NEW YORK.

GASOLENE-TANK AND GAGE FOR SAME.

1,249,010.

Specification of Letters Patent.

Patented Dec. 4th, 1917.

Application filed June 21, 1917. Serial No. 176,088.

To all whom it may concern:

Be it known that I, JOSEPH BORYSZEWSKI, Jr., a citizen of the United States, and a resident of Forks, in the county of Erie and State of New York, have invented a new and Improved Gasolene-Tank and Gage for Same, of which the following is a full, clear, and exact description.

My invention relates to a liquid tank particularly suitable for gasoline, and a gage for indicating the amount of liquid therein.

An object of the invention is to provide a simple and inexpensive tank which will maintain the smallest quantity of gasoline in the lowest part of the tank no matter how the automobile carrying the tank is positioned.

Another object of the invention is to provide a gage for the tank for indicating the amount of gasoline therein.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a longitudinal section through a tank embodying my invention on line 1—1, Fig. 2;

Fig. 2 is a horizontal section on line 2—2, Fig. 1;

Fig. 3 is a side elevation, a portion of the dome being broken out on the line 3—3, Fig. 2;

Fig. 4 is a cross section on line 4—4, Fig. 1;

Fig. 5 is a section on line 5—5, Fig. 3;

Fig. 6 is a horizontal section on line 6—6, Fig. 4; and

Fig. 7 is a cross section on line 7—7, Fig. 1.

Referring to the drawings, 9 is the tank, which is preferably circular in cross section, having its larger diameter in the middle. The ends of the tank are eccentric with the middle, so that the tank bulges on one side, the bulging part 10 constituting the bottom, while the straight part 11 constitutes the top. A dome 12 is provided in the central part of the tank at the top of same. A sprocket 13 is revolvably mounted in the top of the dome, and a chain 14 engages the sprocket. One

end of the chain carries a float 15 which is guided in its movement by rods 16 extending from the bottom of the tank into the inner dome 12', forming a tubular extension on the tank. A cap 13' covers said tubular extension or inner dome. A slot 14' is provided in said cap for the chain 14. The other end of the chain enters a tube 17 which constitutes a guide for a weight 18 secured to the end of the chain in the tube. This weight is to maintain the chain taut during the upward displacement of the float.

A pinion 19 is constrained to revolve with the sprocket 13. The pinion 19 meshes with a gear 20 which is, in turn, in mesh with a rack 21 slidably mounted on the top of the tank; preferably the rack is tubular and fits a rod 22 secured at the ends of the tank and on which said rack is free to slide. The rack carries a pointer 23 which travels along scale 24 secured to the tank, said scale being properly divided for indicating any desired fractions of a gallon. The scale, rack and pointer are covered by a housing 31 which forms a part of the dome 12. It carries a transparent member 32 in front of the scale and pointer.

The tank is provided with wave breakers 25 in the form of transverse sectional walls which break up the movement of liquid in the tank during the propulsion of the vehicle with which the tank may be associated. These partitions clear the tank at the edges so there is communication between the opposite two sides of the partitions.

One of the rods 16 is hollow and provided at the bottom with a valve-controlled outlet 26, an aperture 27 being provided in said hollow rod 16 so that the liquid can pass to said valve-controlled outlet 26. A tube 28 extends from the top to the bottom of the tank near the central part of same. Said tube 28 has a threaded plug 29 at the top through which liquid may be poured, and an aperture 30 near the bottom of the tank through which the liquid enters the tank.

The tapering bottom of the tank causes the liquid therein to accumulate in the central part of same, even when the tank is in an inclined position, and, therefore, the outlet from the tank is generally flooded by the liquid.

I claim:

1. In combination, a tank, a float mounted to move vertically of the tank, a scale

associated with the tank and disposed longitudinally of same, a rack adapted to travel along said scale, a pointer carried by the rack for coöperating with the scale, a gear meshing with the rack, and means from the float to the gear for actuating the same during the movement of the float.

2. In combination, an elongated tank, a float adapted to move vertically of the tank, a dome on said tank, a sprocket revoluble in said dome, a chain from said float to the sprocket, a weight associated with said chain for maintaining the same taut, a scale associated with the tank and disposed longitudinally of same, a movable rack, a pointer carried by the rack coöperating with the scale, and gears in said dome interposed between the rack and sprocket, whereby the rack is moved when the float moves.

3. In combination, a tank of circular cross section having the larger diameter in the middle thereof, the ends of said tank being eccentric with the central part so that an outwardly-bulging portion is formed in the tank, which bulging portion is adapted to form the bottom of said tank, a dome on the top of the tank substantially midway between its ends, a sprocket near the top of the dome, a chain engaging the sprocket, a float associated with one end of said chain, rods from the bottom of the tank engaging the float and forming guides for the same, a weight associated with the other end of the chain, a tubular guide for said weight, a pinion constrained to revolve with the sprocket, a rack slidably mounted on the top of the tank, a pointer carried by the rack, a scale secured to the top of the tank and with which said pointer is adapted to coöperate, a gear in the dome interposed between the pinion and the rack, and a housing for said rack and scale having a transparent member opposite said scale.

4. In combination, a tank of circular cross section having the larger diameter in the middle thereof, the ends of said tank being eccentric with the central part so that an outwardly bulging portion is formed in the middle of the tank, which bulging portion is adapted to form the bottom of said tank, a tubular extension in the central part at the top of the tank, a cover for same, a dome on the top of the tank over said tubular portion, a sprocket near the top of the dome, a chain engaging the sprocket, a float associated with one end of the chain, rods from the bottom of the tank into the tubular portion constituting guides for the float, a weight associated with the other end of the chain, a guide for said weight, a pinion constrained to revolve with the sprocket, a tubular rack slidably mounted on the top of the tank, a pointer carried by the rack, a scale secured to the top of the tank and with which said pointer is adapted to coöperate, a gear in the dome interposed between the pinion and the rack, and a housing for said rack and scale having a transparent member opposite said scale.

5. In combination, a tank having an outwardly-bulging bottom, a float adapted to descend toward the deepest part of the tank, a scale disposed longitudinally of the tank, a rack mounted to travel along the scale, a pointer on said rack and coöperating with the scale, and motion transmission means from the float to the rack.

JOSEPH BORYSZEWSKI, JR.
